(57) **CLAIM**

The ornamental design for a modular floor tile, as shown and described.

DESCRIPTION

FIG. 1 is a top isometric view of a modular floor tile showing our new design;

FIG. 2 is a top plan view of the modular floor tile of FIG. 1; FIG. 3 is a bottom plan view of the modular floor tile of FIG. 1;

FIG. 4 is a left side view of the modular floor tile of FIG. 1; FIG. 5 is a right side view of the modular floor tile of FIG. 1;

FIG. 6 is a front side view of the modular floor tile of FIG. 1;

FIG. 7 is a back side view of the modular floor tile of FIG. 1; and,

FIG. 8 is a top isometric view of the modular floor tile of FIG. 1 shown in a position of use.

The broken lines in FIG. 8 depict environmental subject matter and form no part of the claimed design.

1 Claim, 6 Drawing Sheets
